US00D868867S

(12) **United States Design Patent** (10) **Patent No.:** **US D868,867 S**
(45) **Date of Patent:** **** Dec. 3, 2019**

(54) **CAMERA**

(71) Applicant: **Garmin Switzerland GmbH**,
Schaffhausen (CH)

(72) Inventors: **Camille J. Jean**, Overland Park, KS
(US); **Derrick D. Lenz**, Olathe, KS
(US); **Jason D. Watson**, Olathe, KS
(US)

(73) Assignee: **Garmin Switzerland GmbH** (CH)

(**) Term: **15 Years**

(21) Appl. No.: **29/639,336**

(22) Filed: **Mar. 6, 2018**

(51) LOC (12) Cl. **16-01**

(52) U.S. Cl.

USPC **D16/202**; D16/218

(57) **CLAIM**

The ornamental design for a camera, as shown and described.

DESCRIPTION

FIG. 1 is a front perspective view of a camera according to the present invention;

FIG. 2 is a rear perspective view of the camera;

FIG. 3 is a top view of the camera;

FIG. 4 is a front view of the camera;

FIG. 5 is a bottom view of the camera;

FIG. 6 is a rear view of the camera;

FIG. 7 is a left side view of the camera; and,

FIG. 8 is a right side view of the camera.

The broken lines and the unshaded portions within the broken lines that are shown in the drawings depict portions of the camera that form no part of the claimed design.

1 Claim, 3 Drawing Sheets
